UNITED STATES PATENT OFFICE

2,619,001

CARRIER FOR BRAIDING MACHINES

John E. Chace, Adamsdale, Mass.

Application December 12, 1951, Serial No. 261,252

4 Claims. (Cl. 87—22)

1

This invention relates to braiding machines and to improvements in the carriers used in such machines.

In a braiding machine, several carriers move along a circular track in an intricate back and forth weaving pattern. Each of the carriers carries a spool of the thread to be braided, and the thread is spun from the carriers in accordance with the pattern traveled, to form the braided output of the machine.

The conventional carrier has a base adapted to travel in the track of the braiding machine, with a spindle and two guide posts rising from the base. The spindle carries a spool holding the yarn or thread to be braided while the guide posts support yarn guiding eyelets, a tensioning weight, and a spring for controlling the tension of the weight on the yarn. The tensioning spring is coiled about one of the guide posts, and must be removed from time to time to free it from lint, etc., or to change its strength with variations in the type or size of yarn employed.

The weaving motion of the carrier in the braiding operation is a process of sudden turns at high speed which exerts a twisting force on the guide posts, thereby causing wear on the connecting linkage at the tops of the posts which interferes with the operation and shortens the useful life of the assembly, and sometimes results in a binding of the tensioning weight.

The object of the present invention is to provide an improved construction which will overcome these difficulties found in prior art assemblies. This has been accomplished by a connecting linkage at the top of the guide posts which is rigidly secured to one of the posts and has a recess for holding a cap on the other post, the cap being depressible to enable the post to be sprung free of the connecting linkage.

The invention is explained in more detail by reference to the accompanying sheet of drawings wherein:

Figure 1 is a side elevation of a braider carrier embodying the invention;

Figure 2 is a sectional view of the tops of the guide posts of the apparatus of Figure 1, showing one step of operation in the practice of the invention;

Figure 3 is a view of the apparatus of Figure 2, showing another step in the operation of the invention;

Figure 4 is a plan view of the apparatus of Figure 3; and,

Figure 5 is an enlarged view, partly in section, of one of the guide posts and removable cap of the other figures.

2

The braider carrier of Fig. 1 comprises a base 11 with a spindle 12 and guide posts 13 and 14 rising therefrom. The base 11 has a grooved portion 15 adapted to ride upon the track of a braiding machine (not shown).

The spindle 12 carries a spool 16 which furnishes the yarn to be braided. The yarn is fed, in conventional manner, by way of an eyelet 17 on the guide post 14 to a hook 18 on a weighted tension element 19, and thence through eyelet 20 at the top of guide post 14.

Again in conventional manner, the unwinding of the yarn from the spindle is controlled by the following elements: ratchet 21 on the bottom of the spool 16, a pawl 22 meshing with the teeth of ratchet 21, and a bracket 23 slidable on the post 14 and pivotally linked to the pawl 22. The pawl 22 is pivoted on a pin 24 in the base of the carrier. Its front portion seats against the teeth of the ratchet and prevents rotation of the spool upon the spindle. The rear portion of the pawl 22 has a yoke 25, forming a seat for an extension 26 of the bracket 23.

The tensioning element 19 is slidably mounted on the post 13 with a yoke-like extension embracing the post 14. As thread is taken up in the braiding operation, it pulls against the hook 18 of the tensioning element 19 and draws the element up against the top portion 21 of the bracket 23 which is slidably mounted upon the post 14. This forces the bracket 23 upward along the post 14 and against the spring 28, thereby causing the extension 26 to exert an upward thrust against the upper flange of the yoke 25 which pivots the pawl 22 and releases the ratchet 21.

With the ratchet released, the spool 16 is free to turn, and does so under the influence of the tension on the yarn. As soon as there is sufficient play in the yarn to enable the tensioning element 19 to slide down the guide post, the spring 28 urges the bracket 23 to its normal position at the bottom of post 14 where extension 26 acts upon yoke 25 to pivot the pawl 22 to its former position against the teeth of the ratchet 21 thereby preventing further yarn feeding by the spool 16.

The coil spring 29 is slipped over the top of the post 13 and is held in place by a removable cap 30. It exerts a downward thrust on the tensioning element 19. The strength of this spring must be overcome by tension on the yarn to raise the tensioning element 19 to a position where it can act upon the bracket 23 to trip the pawl 22 and permit yarn to reel from the spool 16. Thus, the spring must be changed to accommodate differences in weight, size, etc. of

different yarns. This is accomplished, in accordance with the invention, by forcing the cap 30 down upon the post 13, as shown in Fig. 2, so that the cap is disengaged from its normal seat in the recess 31 of the connecting link 32. After the cap 30 has been thus unseated, the post 13 is sprung free of the link 32, as shown in Figs. 3 and 4. Then, the cap 30 is removed from the post 13, as shown in Fig. 5, and the spring 29 is slipped off the post and replaced by another.

A coil spring 33 within the cap 30 permits the cap to be pushed down upon the post 13 when the post is to be sprung free, and exerts a force against the top of the post to lock post and cap together when the assembly is in operative position with cap 30 in register with recess 31 in connecting link 32. The link 32 is welded, or otherwise rigidly secured, to the post 14.

in this manner, the entire carrier assembly is held rigid during operation of the machine, and yet facile means is provided for permitting sufficient disassembly to replace or change the spring 29 without causing undue wear on either the guide posts or the connecting link between them.

I claim:

1. A braider carrier having a base, first and second upright members extending upwardly from said base, said first upright having mounted thereon a coil spring and a depressable cap, said second upright being longer than said first and having rigidly attached to its end remote from said base a member protruding over the end of said first upright, said member having in said protruding portion a recess adapted to receive said cap.
  2. A braider carrier having a base, first and second upright members extending upwardly from said base, said first upright having mounted thereon a coil spring and a removable cap, said second upright being longer than said first and having rigidly attached to its end remote from

said base a member protruding over the end of said first upright, said member having in said protruding portion a recess adapted to receive said cap.

- 5   3. A braider carrier having a base, first and second upright members extending upwardly from said base, said first upright having mounted thereon a coil spring and a removable cap, said second upright being longer than said first and having rigidly attached to its end remote from said base a member protruding over the end of said first upright, said member having in said protruding portion a recess adapted to receive said cap, and a spring element between said 10 cap and said first upright whereby said cap is urged into said recess.

15

4. A braider carrier having a base, a spindle for carrying a spool mounted on said base, first and second guide posts also mounted on said base, said first guide post being longer than said second guide post, a tensioning element slidably mounted upon said guide posts, a coil spring mounted co-axially upon one of said guide posts and adapted to press against said tensioning element, a connecting member rigidly attached to said first post and extending into the path of axial extension of said second post, a depressable cap on the end of said second post, and said connecting member having a recess therein adapted to receive said cap.
